Patented June 22, 1920.

UNITED STATES PATENT OFFICE.

GEORGE T. NEWELL, JR., OF BEVERLY, NEW JERSEY.

ELECTRICAL PREHEATING ATTACHMENT FOR AUTOMOBILE INTAKE-MANIFOLDS.

1,344,242.

Specification of Letters Patent. Patented June 22, 1920.

Application filed February 5, 1920. Serial No. 356,372.

To all whom it may concern:

- Be it known that I, GEORGE T. NEWELL, Jr., a citizen of the United States of America, residing at Beverly, Burlington county, 5 State of New Jersey, have invented certain new and useful Improvements in Electrical Preheating Attachments for Automobile Intake-Manifolds, of which the following is a full, clear, and exact description.
- 10 This invention relates to a device applicable to the intake manifold of internal combustion motors for preheating explosive mixtures. One of the objects of my invention is to provide means to facilitate the 15 starting of motors in cold weather, at which time vaporization of explosive mixtures is slow.

To carry out my invention, I provide an 20 electrically heated cartridge or plug insertible in an intake manifold and positioned to lie in the path of the incoming explosive mixture so that it will not only preheat the mixture but break up the same or divide the flow thereof.

25 I will now proceed to describe my invention in detail and point out the novel features thereof in the appended claims, reference being had to the accompanying drawing, wherein:—

30 Figure 1 is a diagrammatic view of an internal combustion motor, the intake of which is provided with my improvement;

Fig. 2 is an enlarged sectional detail view 35 of the preheater, a portion of an intake manifold and preferred form of switch for closing the circuit for same; and

Fig. 3 is a sectional view of a modified form of tip for the preheater.

In the drawing, Fig. 1 illustrates diagrammatically, a motor 3 having the usual intake 40 manifold 4 and carburetor 5. My improved device consists of a metallic casing or chamber 6 closed at the bottom as at 7 and having a lining 8 of some non-conducting heat 45 resisting material, preferably mica. Within the chamber I place a resistance coil 9 having leads 10 and 11. The leads are threaded through a plug 13 of heat resisting electrically non-conducting material having 50 passages 14 and 15 for the leads 10 and 11.

After the coil and plug have been placed in the chamber, I seal the upper end 16 of each passage with some non-conducting material, such as condensite, to prevent water from 55 seeping through said passage into the chamber whereby the coil might be short circ-

cuted with the lead 10. The plug will fit the casing tightly, but will be removable. To hold the plug in place I preferably provide same with a head 18 through which a 60 fastening screw 19 is passed to engage the head 20 of the chamber 6. The chamber will be preferably provided with threads 21 to engage a threaded opening in the manifold 4. The preheater will be preferably attached to the top wall 22 of the manifold 4 directly opposite the duct 23 which is common to both branches 24 and 25 of the manifold. As the chamber 6 extends well into the manifold, it will tend to divide the current 70 of an inflowing explosive mixture and tend to break it up, besides providing a heated member to vaporize same.

To facilitate the breaking up of the current, I may provide the chamber at the 75 bottom thereof with a pointed projection 26, which may be made out of metal formed integral with the chamber or a part attached thereto, as shown in Fig. 3. The projection may also be formed out of lava 80 or other refractory material to retain heat, thereby forming a vaporizer which will be heated by conduction after the motor has been running long enough to heat the manifold.

To heat the coil, I provide a source of 85 electrical energy 27, preferably a battery. The circuit for the preheater will include a switch 28 normally kept open by a spring 29, for instance, the object being to prevent 90 the circuit from being maintained closed for an extended period. To start a cold motor it will be but necessary to close the switch to establish a circuit for a relatively short period, just enough to heat chamber 6. 95 After the switch has been released, the spring will open same; hence it will be impossible to accidentally leave the switch closed after the motor has been started. The heated chamber will preheat the incoming cold mixture, thereby vaporizing same, which will cause the motor to start easily. To attach a separable tip or tip of material different from the material of the chamber, I provide said chamber with a threaded stud 100 30 to engage a threaded opening 31 in the separable tip indicated by 32 in Fig. 3.

Having described my invention, what I claim and desire to secure by Letters Patent is:

1. In combination, an intake manifold 110 consisting of a duct for the passage of a

- combustible mixture and branches therefrom, and an electrically heated device carried by the top wall of the manifold and located within the same, said device extending toward said duct, and means carried by the chamber at its lower end arranged to part the flow of an incoming combustible mixture.
2. In combination, an intake manifold consisting of a duct for the passage of a combustible mixture and branches therefrom, and an electrically heated device carried by the top wall of the manifold and located within the same, said device extend-

ing toward said duct, and a projection carried by the chamber at its lower end to part the flow of an incoming combustible mixture.

3. A preheater for the manifolds of gasoline motors consisting of an electrically heated chamber, and a removable tip extending therefrom.

Signed at New York city, N. Y., this 2 day of February, 1920.

GEORGE T. NEWELL, JR.
